(57) **CLAIM**

The ornamental design for a mobile phone, as shown and described.

DESCRIPTION

FIG. 1 is a front perspective view of a first embodiment of a mobile phone, showing our new design in a folded state;
FIG. 2 is a front view thereof;
FIG. 3 is a back view thereof;
FIG. 4 is a top view thereof;
FIG. 5 is a bottom view thereof;
FIG. 6 is a right side view thereof;
FIG. 7 is a left side view thereof;
FIG. 8 is a back perspective view thereof;
FIG. 9 is a front perspective view thereof, showing our new design in an unfolded state;
FIG. 10 is a back perspective view thereof, showing our new design in an unfolded state;
FIG. 11 is a front perspective view of a second embodiment of a mobile phone, showing our new design in a folded state;
FIG. 12 is a front view thereof;
FIG. 13 is a back view thereof;
FIG. 14 is a top view thereof;
FIG. 15 is a bottom view thereof;
FIG. 16 is a right side view thereof;
FIG. 17 is a left side view thereof;
FIG. 18 is a back perspective view thereof;
FIG. 19 is a front perspective view thereof, showing our new design in an unfolded state;
FIG. 20 is a back perspective view thereof, showing our new design in an unfolded state;
FIG. 21 is a front perspective view of a third embodiment of a mobile phone, showing our new design in a folded state;

(Continued)

FIG. 22 is a front view thereof;
 FIG. 23 is a back view thereof;
 FIG. 24 is a top view thereof;
 FIG. 25 is a bottom view thereof;
 FIG. 26 is a right side view thereof;
 FIG. 27 is a left side view thereof;
 FIG. 28 is a back perspective view thereof;
 FIG. 29 is a front perspective view thereof, showing our new design in an unfolded state;
 FIG. 30 is a back perspective view thereof, showing our new design in an unfolded state;
 FIG. 31 is a front perspective view of a fourth embodiment of a mobile phone, showing our new design in a folded state;
 FIG. 32 is a front view thereof;
 FIG. 33 is a back view thereof;
 FIG. 34 is a top view thereof;
 FIG. 35 is a bottom view thereof;
 FIG. 36 is a right side view thereof;
 FIG. 37 is a left side view thereof;
 FIG. 38 is a back perspective view thereof;
 FIG. 39 is a front perspective view thereof, showing our new design in an unfolded state;
 FIG. 40 is a back perspective view thereof, showing our new design in an unfolded state;
 FIG. 41 is a front perspective view of a fifth embodiment of a mobile phone, showing our new design in a folded state;
 FIG. 42 is a front view thereof;
 FIG. 43 is a back view thereof;
 FIG. 44 is a top view thereof;
 FIG. 45 is a bottom view thereof;
 FIG. 46 is a right side view thereof;
 FIG. 47 is a left side view thereof;
 FIG. 48 is a back perspective view thereof;
 FIG. 49 is a front perspective view thereof, showing our new design in an unfolded state;
 FIG. 50 is a back perspective view thereof, showing our new design in an unfolded state;
 FIG. 51 is a front perspective view of a sixth embodiment of a mobile phone, showing our new design in a folded state;
 FIG. 52 is a front view thereof;
 FIG. 53 is a back view thereof;
 FIG. 54 is a top view thereof;
 FIG. 55 is a bottom view thereof;
 FIG. 56 is a right side view thereof;
 FIG. 57 is a left side view thereof;
 FIG. 58 is a back perspective view thereof;
 FIG. 59 is front perspective view thereof; and,
 FIG. 60 is a back perspective view thereof, showing our new design in an unfolded state.
 The broken lines in drawings show portions of the mobile phone that form no part of the claimed design.

1 Claim, 48 Drawing Sheets
